CLAIM

The ornamental design for a power interface module, as shown and described.

DESCRIPTION

FIG. 1 is a front perspective view of a power interface module of our design;

FIG. 2 is a front plan thereof;

FIG. 3 is a rear plan thereof;

FIG. 4 is a left side view thereof;

FIG. 5 is a right side view thereof;

FIG. 6 is a bottom plan view thereof; and,

FIG. 7 is a top plan view thereof.

All broken lines depict functional features of the power interface module that form no part of the claimed design.

All broken lines and the portions within illustrate portions of the article that form no part of the claimed design.
